UNITED STATES PATENT OFFICE

MARK B. HILL, OF TICONDEROGA, NEW YORK.

SPARK PLUG.

1,416,557.

Specification of Letters Patent. Patented May 16, 1922.

Application filed May 4, 1921. Serial No. 466,656.

To all whom it may concern:

Be it known that I, MARK B. HILL, a citizen of the United States, residing at Ticonderoga, in the county of Essex and State of New York, have invented new and useful Improvements in Spark Plugs, of which the following is a specification.

This invention relates to spark plugs especially adapted for use in internal combustion engines.

An important object of this invention is to provide a spark plug embodying a pair of disks which are rotated by the vibration and operation of the engine so as to provide constantly changing sparking points for increasing the efficiency and economy of operation of the engine.

A further object is to provide a spark plug having simple means whereby the rotatable disks which form the sparking points may be readily renewed when necessary.

The invention forming the subject matter of this application aims also to provide a spark plug which is efficient, simple to apply and cheap to manufacture.

Other objects and advantages of the invention will be apparent during the course of the following description.

In the accompanying drawing forming a part of this application and in which like numerals are employed to designate like parts throughout the same,

Figure 1 is a perspective of the improved spark plug.

Figure 2 is a detail sectional view through the same applied.

Figure 3 is a cross sectional view on lines 3-3 of Figure 2.

In the drawing wherein for the purpose of illustration is shown a preferred embodiment of the invention, the numeral 5 designates the head of an internal combustion engine cylinder, which head is provided with the usual screw-threaded opening 6 for the reception of a spark plug.

The spark plug forming the subject matter of this application includes a shell 8 having its forward portion exteriorly screw threaded as indicated at 9 so that the same may be secured within the opening 6.

The shell 8 receives an insulator 10 held in position by means of a sleeve nut 11 and provided with a longitudinally extending electrode 12 to which an electrical conductor is adapted to be connected in the usual manner.

The forward portion of the electrode 12

is formed with a pair of diverging branches 14 arranged at approximately right angles to each other and terminating in spindles or pivot pins 15. A pair of disks 16 are formed with centrally located openings 17 for the reception of the spindles 15 whereby the several disks are rotatably connected to the center electrode 12. With reference to Figure 2 it will be observed that the spindles 15 by reason of being reduced define annular shoulders 18 with which the inner sides of the disks contact. The outer sides of the disks 16 are engaged by small washers 18' held on the spindles by upsetting the ends 70 of the spindles to form head 20. The inclination of the several branches 14 disposes each disk with its axis extending obliquely with relation to the longitudinal axis of the spark plug whereby the periphery of each 75 disk is presented angularly to the forward end of the shell. Each disk is of course spaced slightly from the shell to define a spark gap over which the current jumps for igniting the gases compressed within the cylinder. The inclination of the disks directs the compressed gases laterally to some extent so that any solid particles of oil which may be suspended in the gas will not be permitted to collect on the disks and the inner 80 wall of the shell.

The collection of carbon on the disks is prevented to a high degree since the disks are rotated constantly by the vibration and the periodical compression and combustion 90 of the gases within the cylinder. This also renders the disks self-cleaning to a high degree.

The edges of the disks are beveled as indicated at 22 so as to present relatively wide 95 and flat surfaces to the lower end of the spark plug whereby the sparks are spread over a relatively wide area for completely igniting the gases.

Having thus described the invention what 100 I claim is:—

1. A spark plug comprising a shell, an electrode extending through the shell and having its forward portion formed with diverging branches having reduced spindles 105 forming shoulders, and disks freely rotatable on said spindles and contacting with said shoulders, the edges of said disks being beveled and arranged in spaced relation to the end of the shell and in spaced relation to each other.

2. A spark plug comprising a shell, an

electrode extended through the shell and having diverging branches terminating in spindles defining annular shoulders, obliquely arranged disks having central openings freely receiving said spindles whereby the disks are free to rotate, the edges of said disks being beveled and arranged in spaced relation to the end of the shell and in spaced relation to each other, and washers 10 formed on the terminal portions of said spindles, the ends of said spindles being upset.

3. A spark plug comprising a shell, an electrode carried thereby, and pair of obliquely arranged disks carried by said electrode and cooperating with the forward end of said shell in forming oppositely arranged spark gaps.

In testimony whereof, I have affixed my signature in the presence of two witnesses. 15

MARK B. HILL.
